CARBURETING APPARATUS

Lynn A. Williams, Jr., Northfield, William A. Marshall, Jr., Chicago, and William F. Gradelph, Jr., Oak Park, Ill., assignors to Stewart-Warner Corporation, Chicago, Ill., a corporation of Virginia

Application January 15, 1945, Serial No. 572,766

2 Claims. (Cl. 261—69)

1

Our invention relates to carbureting apparatus for use particularly in connection with internal combustion engines for controlling the feed of fuel thereto, and has for its principal object the provision of a new and improved form and arrangement of parts whereby the richness of the air and fuel mixture fed to the engine shall be substantially increased momentarily while the throttle is being opened for rapid acceleration. The invention is an improvement on the arrangement shown and described in the prior Williams application, Serial No. 552,651, filed September 4, 1944.

Our arrangement is similar to that shown by said prior application, but includes an auxiliary intake manifold pressure chamber in addition to the intake manifold pressure chamber as shown by the application, such two chambers being connected together so as to cooperate effectively for causing a rich mixture to be fed to the engine when the accelerator pedal is given a substantial downward movement. In our improved arrangement, in which the intake manifold pressure chambers are separated from each other by a flexible diaphragm, when the accelerator is depressed, the increased pressure in the intake manifold brought about thereby is communicated immediately to one of the intake manifold pressure chambers, but the application of such increased pressure effect to the other chamber is retarded during a period of several seconds. The arrangement is such that this differential application of the pressure to the two chambers opens the fuel valve by a small amount additionally for obtaining a richer mixture and maintains such excess opening until the pressure on the opposite faces of the intervening diaphragm has been equalized.

It is one of the objects of our invention to provide an improved arrangement of connecting means between said two chambers for insuring that they will have cooperative action for a limited period for effecting the desired increased opening of the valve.

It is another object of our invention to improve apparatus of this type in sundry details hereinafter pointed out.

The preferred means by which the several objects have been attained are illustrated in the accompanying drawings, in which:

Fig. 1 is a perspective view of a portion of an internal combustion engine provided with a preferred form of our improvements;

Fig. 2 is a central vertical sectional view through the improved valve structure, by which measured amounts of fuel are fed to the engine;

2

Fig. 3 is a diagrammatic view of the upper portion of the engine as seen from the left in Fig. 1; and

Fig. 4 is a vertical sectional view on a considerably enlarged scale, through the float bowl forming part of the means for feeding fuel to the engine.

Referring now to the drawings for a description of the form of device as there shown, 10 indicates an internal combustion engine having an exhaust manifold 11 of any approved type, and an intake manifold 12 provided with ducts 13 leading downwardly to the several cylinders of the engine. At its forward end, the manifold 12 assumes the form of a Venturi tube, indicated by the numeral 14, a throttle valve 15 being movably mounted in position to close the passageway a short distance to the rear of the throat portion of the Venturi tube, and a choke valve 16 being movably mounted in position a short distance ahead of the throat portion. Links 17 and 18 are connected with the valves 15 and 16, respectively, for controlling their position in a well known manner.

25 In the arrangement shown (see Fig. 2), the fuel regulating valve 19 is formed of six casing sections 29, 30, 31, 31a, 32, and 33, connected together by any suitable means, with flexible diaphragms 34, 35, 36, 36a and 37 interposed between the several casing parts to provide a plurality of chambers. By the use of the flexible diaphragms between the several chambers, each of the chambers is given one or more yielding wall portions adapted to be moved inwardly or outwardly in accordance with pressure conditions in the chambers. By the arrangement shown, we have provided a fuel pressure chamber 42 at the bottom of the device, connected by a duct 43 with a second fuel pressure chamber 38 at the top, such duct 43 being formed by connected bores in the casing sections.

Immediately below the fuel pressure chamber 38, there is an air chamber 39, and immediately below that an atmospheric pressure chamber 40. 45 Between the atmospheric pressure chamber 40 and the bottom fuel pressure chamber 42, we have provided, by the construction specified, an intake manifold pressure chamber 41 and an auxiliary intake manifold pressure chamber 41a. The several chambers are operatively connected with the engine 10, in the arrangement shown, by a series of pipes, fittings, and other parts as hereinafter specified for establishing the required communication between the engine and the several chambers whereby the pressure conditions in the en-

gine at different points and under varying circumstances may control the feed of the fuel to the engine.

In the construction illustrated, gasoline or other liquid fuel is supplied to the fuel pressure chamber 42 under constant pressure through a pipe 20 from any suitable source. Measured amounts of the fuel are carried to the lower portion of a closed float bowl 20a from the fuel regulating valve 19 by a pipe 21, and branch pipes 22 lead from the bowl 20a to spray nozzles 23 of any approved type, mounted in the walls of the air ducts 13 in close proximity to the intake valves of the engine cylinders. Communication is established between the air chamber 39 and the throat portion of the Venturi tube 14 by means of a line of piping 24.

A pipe 25, communicating with the atmospheric pressure chamber 40, opens to the atmosphere at any desired point, being shown in the drawings as opening to the atmosphere at a point immediately ahead of the choke valve 16. In many embodiments of the invention, it would be immaterial at what point the opening to the atmosphere was provided, but in some instances where an air filter or a turbo supercharger might be employed, it might be highly desirable to have the parts arranged as shown in the drawings so that the pressure in the chamber reflects any differences from true atmospheric pressure caused by the presence of such a filter or supercharger.

In the arrangement shown in the drawings, communication is established by pipes 27 and 28 between the intake pressure chamber 41 and the intake manifold 12 at a point a short distance to the rear of the throttle valve 12, and by pipes 26 and 29 between the casing member 65, as hereinafter described, and the intake manifold at said point to the rear of the throttle valve. It will be understood that the form of the connections may be varied as desired without departing from the invention, so long as the desired lines of communication are established.

As is clearly shown in Fig. 2, the walls of the casing members 31a and 32 are provided with openings 86 and 87 therein for providing communication between chambers 41 and 41a. In the opening 87, we have provided a check valve 88 in the form of a disk having a small opening 89 therethrough, such valve being movable downwardly against the action of a light coiled spring 90 for permitting free movement of the fluid from the chamber 41a to the chamber 41 through the comparatively large opening in which the valve is mounted. Movement of fluid upwardly from the chamber 41 to the auxiliary chamber 41a, however, is very substantially restricted, since the fluid moving in that direction must pass through the small opening 89. A removable plug 91 is preferably provided for affording access to the spring 90 and the valve disc 88 if it should prove desirable to substitute a valve disc with an opening of a different size therethrough.

For controlling the passage of liquid fuel from the pipe 20 or other source into the fuel pressure chamber 42 for movement to the spray nozzles 23, a needle valve 44 is provided, tapering to a sharp point at its lower end and movably mounted in position to close an opening 45 through a plug 46 mounted in the bottom wall of the casing part 33. A coiled spring 44a normally raises the valve 44 from its closure position. At its upper end, the needle valve 44 engages a pressure plate 47 carried by the diaphragm 37, the diaphragm being gripped between the plate 47 below and a plate 48 above. The diaphragm 36a is gripped between

plates 47a and 48a and the diaphragm 36 between two plates 49 and 50.

In the arrangement shown, the diaphragms 36a and 37 are connected together by means of a pin 48b which is riveted to the plates 47 and 48 and a pin 51 riveted to the plates 47a and 48a. The diaphragms 36 and 36a in turn are connected together by means of the pin 51, a pin 52 riveted to the plates 49 and 50, and a turnbuckle sleeve 10 51a having a notched plate 51b mounted thereon.

The diaphragm 35 is provided with reinforcing plates 53 and 54 which are held in gripping relationship to the diaphragm by a cup-shaped rivet 55 which is connected to the plate 50 by a screw threaded pin 56. The diaphragm 34 also is provided with reinforcing plates 57 and 58 which are held in gripping relationship to the diaphragm by a pin 59 having a riveted connection with said plates, the pin 59 being in axial alignment with the pin 56 and being adjustably connected with said pin by means of a sleeve 60 provided with a notched plate 61 rigidly mounted thereon.

Access to the plates 51b and 61 may be provided 25 in any suitable manner for turning the plates, as by normally plugged openings through the walls of the casing parts, so as to enable an operator to adjust the distance between either the diaphragms 34 and 35 or the diaphragms 36 and 36a.

Above the plate 57 we have mounted a coiled 30 spring 62 bearing at its upper end on the top wall of the casing member 29, such spring being adapted to apply downward pressure on the needle valve 44 through the train of parts as above described. An upward adjustment of the pin 59 by means of either of the turnbuckle arrangements serves, of course, to compress the spring 62 so as to cause it normally to have increased resilient pressure downwardly on the needle valve 44.

With the chambers 38 and 42 filled with gasoline or other liquid fuel supplied under pressure through the pipe 20, such fuel presses upwardly on the diaphragm 37 and acts through the duct 45 43 to press downwardly on the diaphragm 34, serving to apply a differential pressure downwardly on the needle valve 44 by reason of the fact that the diaphragm 34 is of greater effective size than that of the diaphragm 37. Such differential downward pressure of the fuel and the downward pressure of the spring 62 serve normally to hold the needle valve 44 seated so as to prevent the movement of fuel past the valve.

When the choke valve 16 is moved into more 55 or less completely closed position in the air inlet means and the engine is cranked so as to exert a suction effect on the intake manifold 12, such suction effect applied through the pipes 28 and 27 pulls downwardly on the diaphragm 36 and 60 upwardly on the diaphragm 37 within the chamber 41. Under these conditions the diaphragm 36a has very little or no effect, since the valve 88 moves downwardly against the action of the spring 90 for quickly balancing the pressure conditions in the chambers 41 and 41a following the application of the suction effect through the pipes 28 and 27. A differential pressure is thus applied 65 downwardly upon the needle valve 44, by reason of the fact that the diaphragm 36 is of larger effective size than that of the diaphragm 37. At the same time under these conditions, with the choke valve closed and with the crankshaft being rotated for starting the engine, the low pressure condition in the intake manifold exerts a strong suction effect through the pipe 24 upon the dia-

phragms 34 and 35 of the valve chamber 39, serving to apply a strong differential pull upwardly on the diaphragm 35 by reason of the fact that the diaphragm 35 is of very much larger effective size than that of the diaphragm 34.

This upward pull on the diaphragm 35 and the other diaphragms connected therewith leaves the needle valve 44 free to be moved upwardly by the spring 44a so as to permit the passage of a substantial stream of fuel past the valve and so as to produce a rich mixture in the ducts 13 leading to the cylinders for starting the engine. Under the conditions specified, the upward pull on the diaphragm 35 for opening the valve 44 is substantially in excess of the several forces tending to close the valve, resulting in a rich fuel mixture and easy starting of the engine.

As soon as the choke valve is opened and the engine operates at normal idling speed, the suction effect on the pipe 24 drops, since the Venturi tube suction effect on the pipe 24 is very small so long as the volume of air passing through the tube is kept low. The needle valve 44 thereupon closes and an auxiliary fuel feeding valve 63 serves, as hereinafter described, to keep the engine running during any idling period.

With the engine idling after starting, the choke valve 16 being open and the throttle valve 15 being substantially closed, the needle valve 44 remains in its fully closed position. When thereafter the throttle valve 15 is opened for operation of the engine under load conditions with a substantial amount of air being drawn in through the Venturi tube, the suction effect through the pipe 24 is increased so as to cause the diaphragm 37 and the bearing plate 47 to move upwardly for permitting the needle valve 44 to open for the passage of the required amount of fuel. With the throttle valve open, the pressure rises substantially in the intake manifold so that the suction effect through the pipes 28, 27, and 26 is substantially reduced, having the effect of closing the auxiliary fuel feeding valve 63 as hereinafter described, leaving the needle valve 44 under the conditions named in complete control of the delivery of fuel to the cylinders.

When the engine is running under load conditions with the pressure in chambers 41 and 41a fully equalized, the operation of the engine is substantially the same as it would have been if the auxiliary intake manifold pressure chamber had not been employed. When, under such circumstances, the engine is slowed up or stopped by a more or less complete closing movement of the throttle, the suction effect exerted through the pipes 28 and 26 from the intake manifold is increased, serving to cut down the pressure in the chamber 41. The check valve 88 accordingly moves downwardly against the action of the light spring 90 for a substantially instantaneous equalization of the pressure in the chambers 41a and 41.

When the throttle valve is given an opening movement, however, for causing acceleration of the engine, the auxiliary chamber 41a is instrumental in bringing about a highly desired increase in the richness of the fuel mixture. When the throttle valve is opened so as to permit the air to move more freely through the air induction tube, the suction effect in the intake manifold falls off substantially and the pressure in the valve chamber 41 which is connected with the intake manifold by the pipes 28 and 27 is correspondingly increased. There is immediately a tendency for the pressure in the auxiliary chamber 41a to rise

also by the movement of air through the opening 89 from the chamber 41 to the chamber 41a for equalizing the pressure, but such equalization requires a period of several seconds for completion. With the pressure temporarily higher in the chamber 41 than in the chamber 41a, a substantial differential upward pressure is established on the diaphragm 36a so as to bring about an upward opening movement of the valve 44 for causing an increased flow of the liquid fuel past the valve and thus increasing the richness of the mixture delivered to the engine. The opening 89 is designed to be of such size that it shall take only a few seconds for the pressure in the chambers 41 and 41a to become equalized therethrough. When after a few seconds the pressure in the chamber 41a is brought into balance with that in the chamber 41, the differential upward pressure on the diaphragm 36a is brought to an end.

The increased richness of the mixture fed to the engine during the few seconds immediately following the opening of the throttle valve is sufficient for bringing about the highly desired quick pick-up of the motor. For a truck or other heavy car, the opening 89 may be of smaller size than for a light car so as to provide the increased richness of the mixture for a longer period, but in any case the size of the opening 89 may be chosen to fit the conditions expected to be met.

The auxiliary valve means comprising the valve 63 which goes into action for idling operation of the engine, comprises the auxiliary casing member 65 above referred to and a second auxiliary casing member 64 secured by screw threads in the wall of the casing member 33, such casing members 64 and 65 being secured together by screws 66 with a flexible diaphragm 67 secured between the casing members and dividing the enclosed space into chambers 68 and 69. The chamber 68 is connected with the fuel pipe 20 by means comprising an opening 70 in the wall of the casing member 33. The chamber 68 is also connected to the chamber 42 by means of a bored opening 71, a restricted plug 72, and a port 73 in the end wall 74 of the auxiliary casing member 64.

A dome-shaped partition 75 having an opening therethrough at one side is provided across the chamber 68, serving to support a screen 76 in said chamber 68 between the opening 70 and the valve opening 73. The auxiliary valve 63 is connected with the central portion of the diaphragm 67 in position to close the valve port 73, plates 77 and 78 being secured on opposite faces of the diaphragm for reinforcing it, a coiled spring 79 being provided between the plate 78 and a suitable portion of the auxiliary casing member 65 adapted normally to hold the auxiliary valve 63 seated so as to close the valve opening 73.

The arrangement is such that when the engine shaft is turned over for starting the engine, with the choke valve 16 closed and the throttle valve 15 opened, a strong suction effect is exerted on the chamber 69 through the pipes 28 and 26, serving to open the auxiliary valve 63 against the action of the spring 79, permitting fuel to flow through the opening 70, the valve port 73, the bore 71, and the plug 72 into the chamber 42 so as to pass into the pipe 21 with any fuel entering the chamber 42 at the same time through the valve opening 45. After the engine has started and the choke valve has been opened and the throttle valve substantially closed for causing the engine to idle, the needle valve 44 promptly closes as above described, and the

auxiliary valve serves by itself to provide the necessary fuel for idling purposes. The auxiliary valve 63 is then held open against the action of the spring 79 by the continued suction effect transmitted through the pipes 28 and 26, the suction effect through said pipes 28 and 26 being maintained under these conditions by reason of the fact that the throttle valve is practically closed. As soon as the throttle is opened wider for power operation of the engine, the suction effect through the pipes 28 and 26 falls and the spring 79 moves the auxiliary valve 63 to its closed position. Under normal circumstances, the auxiliary valve 63 does not open to permit fuel to pass except when one of the valves 15 or 16 is closed so as to prevent any substantial flow of air to the cylinders.

In the arrangement shown, comprising the spray nozzles 23 for directing fuel to the air ducts 13 immediately adjacent to the cylinders, it is important that the fuel be maintained in liquid form at all parts of the fuel delivery pipes 21 and 22. In order to protect against the effects of vaporization of the fuel in the low pressure feed pipes, an arrangement is provided for promptly removing from the pipe any fuel vapor formed therein. This arrangement comprises a float 80 in the bowl 20a, provided with a pin or stem 81 on its upper face slidably mounted in an opening 82 through a bracket 83 depending from the top wall of the bowl. This bracket is provided with a chamber 84 therein communicating with the opening 82 in which the pin 81 is mounted, such chamber 84 being connected by a pipe 85 with the intake manifold 12. The arrangement is such that the fuel entering through the pipe 21 is free at all times to flow through the pipes 22 to the spray nozzles 23. Any fuel vapor formed in the fuel feeding pipes will, of course, rise into the bowl 20a so as to displace a part of the liquid fuel from the bowl and thus lower the level of the fuel. When the level of the liquid is lowered sufficiently for causing the stem or pin 81 on the float to clear the upper portion of the opening 82 above the chamber 84, the vapor escapes from the bowl through the chamber 84 and the pipe 85 into the intake manifold. The reduced pressure in the bowl by reason of the escape of the vapor permits the entrance of additional fuel by reason of the pressure thereon in the pipe 20, such additional fuel serving to raise the float for again closing the upper end portion of the opening 82, whereupon the flow of additional fuel ceases.

By our improved construction, we have provided an operative arrangement adapted to cooperate effectively with the apparatus with which it is associated without injuriously affecting the operation of such apparatus and adapted by automatic action to bring about temporarily increased richness of the fuel mixture fed to the engine at every opening movement of the throttle valve during the operation of the car. The arrangement is such that the temporary changes in the richness of the mixture are brought about only upon the opening of the throttle valve and that there is no corresponding change for cutting down the richness of the mixture when the throttle valve is given a movement toward its closed position.

While we prefer to employ the form and arrangement of the parts as shown in the drawings and as above described, the invention is not to be restricted thereto except so far as the claims may be so limited, it being understood

that changes might well be made in the form and arrangement of the parts without departing from the spirit of the invention.

We claim:

1. In an apparatus for feeding fuel and air to an internal combustion engine intake, the combination comprising: means forming an air induction passage connected at one end with the intake of the engine, said passage being shaped to form a Venturi portion, means for supplying fuel to said air induction passage, the last said means including a fuel pressure regulating valve, operating means for said valve including diaphragm means connected to be sensitive to the fuel pressure downstream of said valve for tending to close said valve when said downstream pressure rises, second diaphragm means connected to be sensitive to the pressure differential created by flow of air through said venturi for tending to open said valve as said pressure differential rises, third diaphragm means connected to be sensitive on one side to the pressure at said engine intake, means forming a passage leading between the two sides of the last said diaphragm, a check valve in said passage, means forming a leak port between the two sides of said check valve, said check valve being so oriented as to close when the pressure on said one side of the last said diaphragm rises and to open when the last said pressure drops, and means connecting the last said diaphragm to said pressure regulating valve so that the existence of a higher pressure on said one side than on the other side thereof will tend to open said pressure regulating valve, whereby a sudden increase in the pressure at said engine intake will produce a pressure differential across the last said diaphragm tending to open said regulating valve, the last said pressure differential being dissipated over a period of time by leakage through said leak port, whereas a sudden decrease in the pressure at said engine intake will open said check valve and reduce the pressure on both sides of the last said diaphragm substantially equally.

2. In an apparatus for feeding fuel and air to an internal combustion engine intake, the combination comprising: means forming an air induction passage connected at one end with the intake of the engine, said passage being shaped to form a Venturi portion, means for supplying fuel to said air induction passage, the last said means including a fuel pressure regulating valve, operating means for said valve including diaphragm means connected to be sensitive to the fuel pressure downstream of said valve for tending to close said valve when said downstream pressure rises, second diaphragm means connected to be sensitive to the pressure differential created by flow of air through said venturi for tending to open said valve as said pressure differential rises, third diaphragm means connected to be sensitive on one side to the pressure at said engine intake, means forming a passage leading between the two sides of the last said diaphragm, said passage having means therein adapted to permit a substantially unrestricted flow of air from the other side of the last said diaphragm to the said one side thereof and to offer substantial restriction to the flow of air in the opposite direction whereby a sudden increase in the pressure at said engine intake will produce a pressure differential across the last said diaphragm tending to open said regulating valve, the last said pressure differential being dissipated over a period of time by way of the restriction, whereas a sudden decrease in the pressure at said engine intake will reduce the pres-

9

sure on both sides of the last said diaphragm substantially equally.
